[57] **CLAIM**

The ornamental design for a modular over the door sliding hook, as shown and described.

DESCRIPTION

FIG. 1 is a perspective view of an over the door sliding hook according to the present invention;
 FIG. 2 is a front elevational view thereof;
 FIG. 3 is a right side view of FIG. 2, the left side being a mirror image;
 FIG. 4 is a top plan view thereof;
 FIG. 5 is a bottom plan view thereof; and,
 FIG. 6 is a rear elevational view thereof.
